(57) **CLAIM**

We claim the ornamental design for a supporting base for a portable terminal, as shown and described.

DESCRIPTION

FIG. 1 is a perspective front view of a supporting base for a portable terminal according to the present invention.

FIG. 2 is a front elevation view of the supporting base for a portable terminal of FIG. 1.

FIG. 3 is a rear elevation view of the supporting base for a portable terminal of FIG. 1.

FIG. 4 is a right side elevation view of the supporting base for a portable terminal of FIG. 1.

FIG. 5 is a left side elevation view of the supporting base for a portable terminal of FIG. 1.

FIG. 6 is a top view of the supporting base for a portable terminal of FIG. 1; and,

FIG. 7 is a bottom view of the coded information reader of FIG. 1.

Broken lines and unshaded portions contained within broken lines are not claimed.
